CLAIM

The ornamental design for a wash sink, as shown and described.

DESCRIPTION

1.3 Wash sink

1.1 is a perspective view.

1.2 is a side view.

1.3 is a front view.

1.4 is another perspective view.

1.5 is another perspective view.

1.6 is a top view

1.7 is a bottom view.

2.1 is a perspective view.

2.2 is another perspective view.

2.3 is a front view.

2.4 is a side view.

3.1 is a perspective view.

3.2 is a top view.

3.3 is a front view.

3.4 is a side view.

3.5 is another perspective view.

3.6 is another perspective view.
